UNITED STATES PATENT OFFICE.

JAMES W. JENNER, OF LOUISVILLE, KENTUCKY.

ENGRAVING-PLATE HOLDER.

1,347,101.

Specification of Letters Patent. Patented July 20, 1920.

Application filed May 29, 1920. Serial No. 385,097.

To all whom it may concern:

Be it known that I, JAMES W. JENNER, a citizen of the United States, residing at Louisville, in the county of Jefferson and 5 State of Kentucky, have invented certain new and useful Improvements in Engraving-Plate Holders, of which the following is a specification.

This invention relates to improvements in 10 engraving-plate holders, and has for its particular object to provide a means whereby a plurality of engraving plates can be assembled in a manner that they can be inked at one time, polished simultaneously, and 15 imprints taken from all of them in one impression.

Another object of the invention is to provide an engraving-plate holder in which 20 engraving plates can be held rigidly against lateral movement without the use of locking attachments usually employed in printing and engraving shops, and in a manner to avoid leaving sharp edges exposed between the plates themselves and the contacting portions of the plate holder.

These and other objects hereinafter set forth are attained by the means illustrated in the accompanying drawing, in which:—

Figure 1 is a perspective view of the improved engraving-plate holder.

Fig. 2 is a longitudinal vertical section through the holder showing a series of engraving plates mounted therein, and

Fig. 3 is a transverse vertical section of 35 the same, also showing engraving plates mounted therein.

Similar reference numerals in all of the figures of the drawing designate like parts.

The present method of printing name or 40 other cards, usually from copper engraving-plates, consists of taking a single plate and securing it to a suitable bed, then inking the one plate, next polishing the same, and finally making the impression. This slow 45 and tedious method of engraving only one card at a time requires the full service of one engraver, and consequently makes the product costly, and in view thereof, it is one of the important objects of this invention, to provide a means for holding a plurality of separate engraved card-plates each containing a different inscription, and in a manner, whereby one engraver can ink, 50 polish, and print a plurality of cards at one time.

This improved engraving-plate holder is

preferably formed from a steel block of a thickness of approximately one-half an inch, and is formed on one side thereof with a plurality of recesses 5, which are preferably formed by planing, and each recess is of a depth slightly more than the thickness of the engraved plates to be printed from, and of a width equal to the width of said engraved plates, and preferably of a length 60 equal to the combined length of three individual plates, and forming a marginal border having vertical walls 6 around the holder, and divisional borders having vertical walls 7 between the recesses. With a 65 holder of this particular size, nine individual card-plates can be inked at one time, and polished simultaneously, and their inscriptions be transferred to a single sheet of paper or cardboard with one impression 70 of the press. After the required number of impressions have been made, the printed sheet is cut to the desired size of individual cards.

The recesses are formed slightly deeper 80 than the usual copper engraved plates 8, so that a layer of suitable tag-board 9 can be placed beneath the copper plates, not only to form a cushion for the plates, but also to build or elevate varying thicknesses of 85 copper plates so that their upper surfaces will be flush with the upper surfaces of the marginal and divisional borders. Thus the upper exposed portions of the holder and the upper surfaces of the copper plates being flush, an operator, with his hands, or with the wiping cloth of a power press, can 90 polish the whole number of plates at one time as a single unit.

It is not necessary that the holder be completely filled with plates, as one or more can be secured therein if the occasion demands, and the holders can be made of varying sizes governed by the size of the plate-press used.

In operation, when an engraver is supplied with a plurality of orders for differently engraved cards, he places the engraved plates of the cards desired in the holder, first inserting the tag-board base to secure 100 a flush surface, and if desired using wax to fasten the plates in position and prevent their accidental displacement, and then the whole, as a unit, is inked and polished either manually or mechanically, and finally printed 105 in the usual manner, using only one sheet of paper or cardboard and afterward cut- 110

ting to the desired sizes. In this operation of printing nine cards in this manner, one engraving printer does the work of nine with very little extra trouble, thereby decreasing the cost of the product to a great degree.

It will be understood that any hard material can be used for the holder other than steel, and, furthermore, that the size and dimensions thereof can be varied to suit different conditions.

Having thus fully described the invention, what is claimed is:—

1. An engraving-plate holder, comprising a hard block of material having a recess in one side to provide vertical retaining walls, said recess being of a depth slightly greater than the thickness of the plate to be printed from, and of a width equal to the width of said plate, whereby when the plate is positioned in the holder it is held rigidly between the vertical walls and flush with the upper surfaces thereof.

2. An engraving-plate holder, comprising a hard block of material having a recess in one side thereof to provide vertical retaining walls, said recess being of a depth

slightly greater than the thickness of the plates to be inserted therein, and of a width equal to the width of one of said plates, and of a length equal to the multiple of the length of one of the plates, whereby when a series of plates are positioned in the holder and cushioned with their adjacent ends abutting they will be held rigidly between said vertical walls and flush with the upper surfaces thereof.

3. An engraving-plate holder, comprising a hard block of material having a plurality of recesses in one side thereof to provide vertical retaining walls around each recess, each of said recesses being of a depth slightly greater than the thickness of the plates to be inserted therein, and of a width equal to the width of one of said plates, and of a length equal to the multiple of the length of one of the plates, whereby when a series of plates are positioned in the holder and cushioned with their adjacent ends abutting they will be held rigidly between said vertical walls and flush with the upper surfaces thereof.

In testimony whereof I affix my signature.

JAMES W. JENNER.
